UNITED STATES PATENT OFFICE

164,702

MARIMBA

Lowell H. Montz, La Verne, Calif.

Application August 14, 1950, Serial No. 11,750

Term of patent 3½ years

(Cl. D56—1)

To all whom it may concern:

Be it known that I, Lowell H. Montz, a citizen of the United States, residing in La Verne, in the county of Los Angeles and State of California, have invented a new, original, and ornamental Design for a Marimba, of which the following is a specification, reference being had to the accompanying drawings, forming a part thereof.

The back portion of the keyboard section is conventional.

I claim:

The ornamental design for a marimba, substantially as shown and described.

LOWELL H. MONTZ.
